(57) **CLAIM**

The ornamental design for a storage device, as shown and described.

DESCRIPTION

FIG. 1 is a top front right-side isometric view of a storage device showing my new design;

FIG. 2 is a top rear left-side isometric view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof.

FIG. 9 is a top front right-side isometric view of a storage device showing my new design in an exploded state with the lid in an open position;

FIG. 10 is a top rear left-side isometric view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof;

FIG. 16 is a bottom plan view thereof.

FIG. 17 is a top front right-side isometric view of an alternative embodiment of my new design;

FIG. 18 is a front elevation view thereof, with the rear view, the right side view, and the left side view being identical;

FIG. 19 is a cross section view taken along line 19-19 of FIG. 18 thereof;

FIG. 20 is a top plan view thereof;

FIG. 21 is a bottom plan view thereof.

FIG. 22 is a top front right-side isometric view of another alternative embodiment of my new design;

FIG. 23 is a front elevation view thereof, with the rear view, the right side view, and the left side view being identical;

FIG. 24 is a cross section view taken along line 24-24 of FIG. 23 thereof;

FIG. 25 is a top plan view thereof; and,

FIG. 26 is a bottom plan view thereof.

The broken lines in the drawings depict portions of the storage device that form no part of the claimed design.

1 Claim, 16 Drawing Sheets
